UNITED STATES PATENT OFFICE.

BREWSTER S. BEACH, OF WHITE PLAINS, NEW YORK, ASSIGNOR TO AMERICAN GAS PRODUCTS CORPORATION, OF NEW YORK, N. Y., A CORPORATION OF NEW YORK.

GAS COOKING STOVE.

Application filed January 8, 1927. Serial No. 159,762.

My invention relates to gas cooking stoves, and more particularly to an improvement in stoves of this type capable of use either for cooking purposes or as a table.

5 At the present time in large cities with the increased number of apartment houses, small kitchens or kitchenettes are commonly provided. The floor space allotted to the kitchen or the kitchenette is so small, as a rule, as to necessitate not only the use of 60 small kitchen equipment, but to provide inadequate accommodations for a convenient full equipment of the room.

10 With the above conditions in mind, I have 65 provided a gas cooking stove in which the splash or back plate is not only so mounted in relation to the top plate of the stove, as to permit it to be turned down or folded upon the top plate, when it is desired to use the 70 stove as a table, but is provided with a deep flange which, when the splash or back plate is raised, will serve as a high shelf for use while the stove is in use, and when said splash or back plate is lowered, will afford 75 a more or less rigid support or apron for the free edge of this plate and at the same time serve as a shield to prevent the accidental opening of any of the gas cocks while the stove is in use as a table.

20 The splash or back plate structure is provided with side frames and brackets, which 80 not only afford a proper support for the shelf and apron forming flange, and the desired rigidity at the opposite sides of the 85 splash or back plate, but by engagement with the manifold pipe, will sustain the load upon the splash or back plate while it is in use as a table top.

25 One or both of the side frames of the 90 splash or back plate is provided with a latch mechanism which by co-operation with the top plate of the stove, holds the splash or back plate with sufficient rigidity when it is raised to permit the use of the flange thereon 95 as a shelf, and may nevertheless be quickly and conveniently released to permit said splash or back plate to be turned downwardly in a manner to permit the use of the stove as a table.

30 The invention consists primarily in a gas 100 cooking stove embodying therein a top plate, a splash or back plate structure, offset hinges connecting the lower portion of said structure with said top plate, said structure having a shelf adjacent the top thereof, and 105

means carried by said splash or back plate structure and said top plate, whereby said splash or back plate structure may be firmly held in the raised position or be permitted to turn upon said hinges; and in such other 110 novel features of construction and combination of parts as are hereinafter set forth and described, and more particularly pointed out in the claims hereto appended.

Referring to the drawings,

Fig. 1 is a front view, in perspective, of a 115 stove embodying the invention;

Fig. 2 is a side view of the upper portion 120 of the stove with the splash or back plate in the raised position; and

Fig. 3 is a similar view with said plate in the lowered position.

Like letters refer to like parts throughout the several views.

In the embodiment of the invention shown 125 in the drawings, I have illustrated my invention in connection with a well known type of gas stove having the usual oven *a*, broiler *b* and flanged top plate *c*. The top plate *c* may be of the open grid or solid top type, 130 which latter is provided with the usual openings closed by means of lids.

Along the front of the stove is a manifold *d* provided with the usual gas cocks indicated at *e*. The stove shown has three top 135 burners and one oven burner, although the number and arrangement of burners is immaterial to the invention.

This general construction and arrangement is old and well known in this art, my 140 invention relating to means in stoves of this general type by which such a stove may be quickly converted into a table for general use or for use in connection with the oven or the broiler.

Secured to the top plate *c*, toward the top 145 and adjacent opposite sides thereof, are hinge members *f*—*f'* having rearwardly extending elongated straps to which is secured the forward portion of bases *g*—*g'* of side 150 frames *h*—*h'* supporting a splash or back plate *i*, which may be, if desired, of enamel or porcelain coated metal stock. Each of the side frames *h*—*h'* is provided with a forwardly extending bracket *j*—*j'* and top side 155 bars *k*—*k'* supporting a metallic shelf *m* adjacent the top of the splash or back plate *i*.

The brackets *j*—*j'* are so spaced with relation to the hinges *f*—*f'* that when the frames *h*—*h'* have been turned forwardly 160

and downwardly about these hinges, said brackets $j-j'$ will come to rest upon the manifold pipe d . The offsetting of the hinges $f-f'$ with relation to the portions of the frame carrying said splash or back plate i is such as to ensure said frames occupying a substantially horizontal position when they are so turned about said hinges.

The splash or back plate structure including said side frames $h-h'$ is double faced, the splash or back plate i forming one face, and a rear plate n secured to the other side of said frames forming the other face of said structure. This plate n is of fairly stiff metal stock, and may be coated with enamel or porcelain or otherwise finished to afford a readily cleanable surface. This plate n , when the frames are turned forwardly and downwardly in the manner above described about the hinges $f-f'$, serves as a table top. The arrangement of said hinges and of the brackets $j-j'$ and bars $k-k'$ as well as of the hinges $f-f'$ and bases $g-g'$, will not only afford a rigid support for said plate n but will so space it away from the top plate as to avoid possible burning of the finish of the splash or back plate i .

Carried by either or both side frames $h-h'$ is a latch member o , pivoted upon one of the stove bolts used in securing the plates i and n upon said frames. This latch member o has a hooked end adapted to pass under and engage the rear flange of the top plate c . Acting upon this latch member is a spring o' , having a normal tendency to cause and maintain engagement of said latch member o with said flange when the back plate structure is in the raised position. The latch o is provided with a thumb piece o^2 by means of which it may be rotated against the tension of the spring to disengage it from the top plate and permit the splash or back plate structure to be turned down to the position shown in Fig. 3.

When the splash or back plate structure is in the raised position, as shown in Figs. 1 and 2, the plate m is in a horizontal position and may be used as a high shelf. When, however, this structure is in the lowered position as shown in Fig. 3, said plate m is positioned vertically so as to act as an apron to the table into which the stove is converted by the turning down of this structure, and also serves to so shield the gas cocks as to prevent any possible accidental opening of these cocks. The relation of parts, in fact, is such that if any of the gas cocks be opened, the edge of said shelf plate m will contact with same before the brackets $j-j'$ engage the manifold d . While it might be possible to close down the splash or back plate structure while one or more of these cocks e is slightly open, this is not at all objectionable, since it will permit the entire plate m to be

used as a heat table for keeping food in the proper condition.

When it is desired to fold the splash or back plate structure to convert the stove into a table, it is merely necessary to disengage the latch or latches o from the flange of the top plate c and pull the entire splash or back plate structure forwardly of the stove, the arrangement being such that the release of these latches will not permit the toppling of this structure in a manner to cause accidental injury to the user of the stove. When it is desired to raise the top plate, it is merely necessary to swing it about the hinges $f-f'$ and permit it to drop into a vertical position, the latches automatically engaging the flange of the top plate and retaining the structure in this position.

The construction and arrangement of parts is such that when in use as a stove, the conditions will be those ordinarily found in stoves of this kind, and the additional cost of a stove embodying the invention as compared with the ordinary stove, is but little more than that of furnishing the rear facing plate n , the latch or latches o and the hinges $f-f'$.

It is not my intention to limit the invention to the precise details of construction shown in the drawings, it being apparent that such may be varied without departing from the spirit and scope of the invention.

Having described the invention, what I claim as new and desire to have protected by Letters Patent, is:—

1. A gas cooking stove embodying therein a top plate, a splash or back plate structure the rearward face of which is adapted to serve as a table top, offset hinges connecting the lower portion of said structure with said top plate, said structure having a shelf adjacent the top thereof on the same side thereof as said offset hinges, whereby when said back plate structure is in one position it may be used as a table, and said shelf will act as an edge apron therefor, and when in the other position said shelf will serve as an ordinary shelf, and means carried by said splash or back plate structure and said top plate, whereby said splash or back plate structure may be firmly held in the raised position or be permitted to turn upon said hinges.

2. A gas cooking stove embodying therein a top plate, a splash or back plate structure the rearward face of which is adapted to serve as a table top, offset hinges connecting the lower portion of said structure with said top plate, said structure having a shelf adjacent the top thereof on the same side thereof as said offset hinges, whereby when said back plate structure is in one position it may be used as a table, and said shelf will act as an edge apron therefor, and when in

the other position said shelf will serve as an ordinary shelf, and a spring-pressed latch member carried by said splash or back plate structure and adapted to operatively engage 5 said top plate, whereby when said latch member is released, said splash or back plate structure may be permitted to turn upon said hinges, and when said structure is raised, the 10 automatic engagement of said latch member with said top plate will firmly hold said structure in the raised position.

3. A gas cooking stove embodying therein a top plate, side frames each having a forwardly extended bracket toward the top 15 thereof, a shelf supported from said brackets, plates upon opposite sides of said frames forming respectively a back or splash plate and a table top, said brackets being so positioned as to engage a portion of the stove 20 adjacent the front thereof when in the lowered position, hinges connected with said side frames and said top plate respectively, said hinges being offset with relation to said frames to an extent substantially corresponding 25 with the extent of projection of said brackets, whereby when said frames are turned downwardly, the plates carried by said frames will be in a substantially horizontal position and said shelf will be in a 30 substantially vertical position adjacent the forward edge of said top plate, and a spring-pressed latch member carried by a side frame adapted to operatively engage said top plate, whereby when said latch member is released, said frames and the plates carried thereby may be permitted to turn upon said hinges, and when said structure is raised, the automatic engagement of 35 said latch member with said top plate will firmly hold said side plate in the raised position.

4. A gas cooking stove embodying therein a top plate, a gas manifold at the front of 40 the stove adjacent said plate, side frames each having a forwardly extended bracket toward the top thereof, said frames being of a height to cause said brackets, when said frames are turned down, to engage said 45 manifold, a shelf supported from said brackets whereby when said frames are turned downwardly, said shelf will shield said manifold, hinges connected with said side frames and said top plate respectively, said 50 hinges being offset with relation to said frames to an extent substantially corresponding with the extent of projection of said brackets, whereby when said frames are turned downwardly, the plates carried by said frames will be in a substantially horizontal position, and a spring-pressed latch member carried by a side frame adapted 55 to operatively engage said top plate, whereby when said latch member is released, said frames and the plates carried thereby may be permitted to turn upon said hinges, and when said structure is raised, the automatic engagement of said latch member with said top plate will firmly hold said side plate in the raised position.

5. A gas cooking stove embodying therein a top plate, side frames each having a forwardly extended bracket toward the top 65 thereof, a shelf supported from said brackets, plates upon opposite sides of said frames forming respectively a back or splash plate and a table top, said brackets being so positioned as to engage a portion of the stove 70 adjacent the front thereof when in the lowered position, hinges connected with said side frames and said top plate respectively, said hinges being offset with relation to said frames to an extent substantially corresponding 75 with the extent of projection of said brackets, whereby when said frames are turned downwardly, the plates carried by said frames will be in a substantially horizontal position and said shelf will be in a 80 substantially vertical position adjacent the forward edge of said top plate, and a spring-pressed latch member carried by a side frame adapted to operatively engage said top plate, whereby when said latch member is released, said frames and the plates carried thereby may be permitted to turn upon said hinges, and when said structure is raised, the automatic engagement of 85 said latch member with said top plate will firmly hold said side plate in the raised position.

6. A gas cooking stove embodying therein a top plate, a gas manifold at the front of the stove adjacent said plate, side frames each having a forwardly extended bracket toward the top thereof, said frames being of a height to cause said brackets, when said frames are turned down, to engage said manifold, a shelf supported from said brackets whereby when said frames are turned downwardly, said shelf will shield said manifold, hinges connected with said side frames and said top plate respectively, said 95 hinges being offset with relation to said frames to an extent substantially corresponding with the extent of projection of said brackets, whereby when said frames are turned downwardly, the plates carried by said frames will be in a substantially horizontal position, and a spring-pressed latch member carried by a side frame adapted 100 to operatively engage said top plate, whereby when said latch member is released, said frames and the plates carried thereby may be permitted to turn upon said hinges, and when said structure is raised, the automatic engagement of said latch member with said 105 top plate will firmly hold said side plate in the raised position.

In witness whereof I have hereunto affixed my signature this 18th day of December, 1926.

BREWSTER S. BEACH.
